Primary Examiner — T Chase Nelson*Assistant Examiner* — Sydney Margaret Parsley(74) *Attorney, Agent, or Firm* — Daniel M. Cohn;
Howard M. Cohn(57) **CLAIM**

The ornamental design for a pet pool, as shown and described.

DESCRIPTION

FIG. 1 is a perspective view of a pet pool showing my new design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is bottom plan view thereof.

The broken lines illustrate portions of the pet pool that form no part of the claimed design.
